UNITED STATES PATENT OFFICE.

IRA C. DRAKE, OF ROCHESTER, WASHINGTON.

UNDERCUTTER GUIDE FOR CROSSCUT-SAWS.

1,277,050.

Specification of Letters Patent. Patented Aug. 27, 1918.

Application filed September 1, 1916. Serial No. 118,064.

To all whom it may concern:

Be it known that I, IRA C. DRAKE, a citizen of the United States, residing at Rochester, in the county of Thurston and State of Washington, have invented certain new and useful Improvements in Undercutter Guides for Crosscut-Saws; and I do hereby declare the following to be a full, clear, and exact description of the invention, such as will 5 enable others skilled in the art to which it appertains to make and use the same.

The invention relates to improvements in undercutter guides for cross cut saws.

The object of the present invention is to 15 improve the construction of undercutter guides for cross cut saws and to provide a simple, practical and efficient undercutter guide of strong, durable and inexpensive construction equipped with an ordinary 20 chisel adapted to support the guide on a log and capable of being removed and being used to cut off slabs for releasing a saw should the same become necessary.

A further object of the invention is to provide 25 an undercutter guide of this character equipped with means for enabling the guide support and the chisel to be adjusted independently of each other and to be secured in their adjustment by a single clamping operation.

With these and other objects in view, the invention consists in the construction and novel combination of parts hereinafter fully described, illustrated in the accompanying 35 drawing, and pointed out in the claims here-to appended; it being understood that various changes in the form, proportion, size and minor details of construction, within the scope of the claims, may be resorted to 40 without departing from the spirit or sacrificing any of the advantages of the invention.

In the drawings—

Figure 1 is a plan view of an undercutter 45 guide constructed in accordance with this invention,

Fig. 2 is a side elevation of the same illustrating the manner of mounting the device on a log,

Fig. 3 is an elevation illustrating the opposite side of the device and showing the

manner of supporting and guiding a cross cut saw,

Fig. 4 is a transverse sectional view on the line 4—4 of Fig. 2, 55

Fig. 5 is a detail sectional view illustrating the construction of the rotary cylindrical member of the clamp,

Fig. 6 is a detail perspective of the 60 slidable tubular member of the clamp,

Fig. 7 is a detail perspective view of the plug.

Like numerals of reference designate corresponding parts in the several figures of the drawings. 65

In the accompanying drawings in which is illustrated the preferred embodiment of the invention, the undercutter guide comprises in its construction, a relatively rotary cylindrical clamping member 1 and a 70 slidable tubular transversely disposed support 2 provided with a longitudinal slot 3 for the reception of a chisel 4 and interiorly threaded at one end 5 of its bore or opening 6. The cylindrical clamping member and 75 the pivot are capable of relative rotary adjustment throughout a complete revolution owing to the mounting of the cylindrical member on the outer end of the tubular pivot member beyond the clamping means 80 hereinafter described. The cylindrical clamping member is provided at its inner end with an inwardly extending annular flange 7 forming a bearing for the slidable tubular support and arranged on the same 85 and the said slidable tubular support is provided at the end opposite that which is interiorly threaded, with an exteriorly arranged projecting annular flange 8 located within the cylindrical rotary member 1 and 90 engaging the flange 7 thereof. The cylindrical member 1 is provided with opposite openings 9 through which passes an arm 10 of a guide support. The arm 10 which constitutes the body of the guide support is 95 provided at its lower end with a shaft 11 upon which is mounted a grooved guide wheel 12 secured to the shaft 11 in proper position thereon by inner and outer cotter pins 13 or other suitable fastening devices, 100 washers 14 being interposed between the ends of the grooved saw guiding roller or

wheel 12. The arm 10 extends downwardly through the opposite openings 9 of the cylindrical member 1 and it is adapted to be adjusted upwardly and downwardly and the 5 said cylindrical member is capable of rotary movement on the slidable tubular support to arrange the supporting arm 10 in the desired position. The chisel is of the ordinary construction and when removed from the 10 device may be employed for various purposes. It is adapted to be driven into a log 15 in the usual manner and the tubular support 2 on which the cylindrical rotary member is adapted to turn, may be moved in- 15 wardly and outwardly on the blade of the chisel to arrange the guide wheel the desired distance from the log 15 so that a saw 16 may be supported and guided by the grooved wheel 12 and maintained in proper position 20 with relation to the log. The interiorly threaded slidable support 2 receives a clamping or adjusting screw 17 provided with a suitable handle 18 and adapted to engage one edge of the chisel as clearly shown in 25 Fig. 4 of the drawings. This adjusting of the screw 17 simultaneously forces a plug 19 into engagement with the inner side edge of the arm 10. The wedge 19 is interposed between the arm and the inner side edge of 30 the chisel. It will thus be seen that the screw engages the outer side edge of the chisel 4 and forces the latter against the adjacent end of the plug 19 and causes the same to engage and clamp the supporting 35 arm between it and the outer walls of the openings 9. By this construction a simple, effective and quick acting single adjustment is provided for securing both the arm and the chisel to the support and rotary mem- 40 ber of the clamp. The chisel is adapted to be readily driven into a log for supporting the undercutter guide and it is adapted for cutting off slabs that often split down in cutting the log.

45 In practice the log will split down and a small slab will catch the saw so that it has to be cut loose and while the chisel is especially advantageous for this purpose it may be employed for a variety of other purposes 50 where a tool of this character is desired and also a similar instrument may be substituted for the chisel as will be readily understood.

What is claimed is:—

- 55 1. A device of the class described comprising a hollow tubular support having a longitudinal slot terminating short of the ends thereof, an outwardly directed flange at the inner end of said support, a hollow cylindrical head mounted upon said support and projecting beyond the inner end thereof and provided with aligned openings in its sides, said head being adapted to be rotated and moved axially upon said support, an inwardly

directed flange at the inner end of said head 65 adapted to coöperate with the flange of said support to prevent the displacement of the head in one direction, a tool passing through the slot of said support and adapted to prevent the displacement of the head in the re- 70 verse direction, an arm passing through the slots in the head, a roller carried by the arm, a pin carried by the support between and engaging the tool and arm, and a tail bolt threaded to the other end of the support and adapted to be adjusted into engagement with the tool to lock all the parts 75 against any relative movements.

2. A device of the class described includ- 80 ing a tubular support having a longitudinal slot therein, an exterior flange at one end of said support, a cylindrical member rotatably mounted on said support and about said flange, a tool extended through said slot of the support for holding the cylindrical 85 member against movement thereon, an arm extending through said cylindrical member outwardly beyond the flange, a pin located in said support and having one end bearing against the inner edge of the tool and its 90 opposite end against one edge of the arm, and a tail bolt threaded to the outer end of the support and adapted to be adjusted into engagement with the tool to lock all the parts 95 against relative movement.

3. A device of the class described includ- 100 ing a tubular support having a longitudinal slot therein, an exterior annular flange at one end of the support, a cylindrical mem- 105 ber rotatably mounted on and about the flange of the support, a tool extending through the slot of the support and limiting the movement of the cylindrical member in one direction thereon, an arm extended through the cylindrical member beyond the flange of the support, a pin located in the support and bearing against the arm and tool, and a tail bolt fitted in the open end 110 of the support and adapted to be adjusted into engagement with the tool for holding and locking all the parts against relative movement.

4. An undercutter guide of the class de- 115 scribed including a tubular pivot member having a longitudinal opening interiorly threaded at one end, said pivot member being provided with a longitudinal slot and having an annular flange at the end oppo- 120 site that which is interiorly threaded, a cylindrical rotary member provided at its inner end with an inwardly extending annular flange fitted on and receiving one end of the pivot member and arranged contiguous to the flange thereof, said cylindrical member being provided with opposite open- 125 ings, a supporting arm arranged within the said openings of the cylindrical member and provided with saw guiding means, a

chisel located within the said slot of the pivot member, a plug interposed between the chisel and the supporting arm and an adjusting screw mounted in the threaded 5 end of the pivot member engaging the chisel whereby the chisel and the supporting arm are clamped in a single operation.

In testimony whereof I affix my signature in presence of two witnesses.
